UNITED STATES PATENT OFFICE.

FRANS O. LIDHOLM, OF CHICAGO, ILLINOIS.

BOX-COVER OPENER.

1,084,093.

Specification of Letters Patent.

Patented Jan. 13, 1914.

Application filed December 6, 1912. Serial No. 735,214.

To all whom it may concern:

Be it known that I, FRANS O. LIDHOLM, a citizen of the United States, residing at Chicago, in the county of Cook and State 5 of Illinois, have invented certain new and useful Improvements in Box-Cover Openers, of which the following is a specification.

My invention relates to means for loosening tightly fitting covers and has particular 10 reference to blacking box covers which are usually fitted tightly in order to prevent a too rapid drying of the contents.

The object of my invention is to improve upon the various forms of cams and levers 15 heretofore provided for this purpose by providing a construction which reduces the number of parts required for the lever-type of opener which forms the subject of my invention.

20 Another object is to provide a positively engaging lever which shall not miss its engagement, or slip, or depend upon a closely fitting pivot joint for dependable operation. And my invention further consists in the 25 various details of construction and advantages hereinafter described in detail, illustrated in the accompanying drawing and incorporated in the appended claims.

20 In the drawing—Figure 1 is a perspective view of a blacking box and cover equipped with my improvement. Fig. 2 is an enlarged section of the box and cover showing in elevation the cover-opening or loosening mechanism. Fig. 3 is a section taken on the 35 line 3—3 of Fig. 2. Fig. 4 is a perspective view of the lever alone. Fig. 5 is a perspective view of a modified form of lever.

In the several views 2 represents the box 40 provided with the usual bead or cover stop 2', and 3 is the cover. In the present invention the lever is mounted on the cover, no operation being made to change the form 45 of the box. In the rim or flange of the cover is cut out an opening 4, a portion of the material struck out being formed into ears or lugs 5 and 6 which are thus made integral 50 portions of the rim or flange of the cover and may be formed at the same operation that produces the opening 4. A lever of the 55 construction shown in Fig. 4 is formed with a pair of ears 7 and 8 which are mounted on a pivot 9 supported by the ears 5 and 6. The upper end 10 of the lever is arranged to project above the edge of the box 2, as 60 shown in Fig. 3, and to engage said edge to pry loose the cover. The lower end of

the lever numbered 11 is curved outwardly from the box and serves as a convenient finger-hold for the operator. In forming the opening 4 the upper edge of it is swelled 60 out as at 12 to form a recess for the end 10 and thereby make that portion of the lever flush with the inner surface of the cover flange and form a substantially air-tight junction between the lever and cover. This 65 also prevents the lever from swinging inwardly when the cover is removed so as to bring its portion 11 in the way when the cover is to be replaced on the box.

In Fig. 5 a modification is shown wherein 70 the ears 7 and 8 are provided with stops 13 and 14 which limit the upward swing of the lever and prevents it when the cover is removed from standing up against the side of the cover flange and make it necessary to 75 lower the lever by hand. By thus limiting the upward swing of the lever it will always drop back by gravity to its normal position and not require adjustment before the lid or cover is replaced as in many forms of 80 blacking box opening devices. As will be noticed, particularly by reference to Fig. 3, there is no chance for the lever to miss its engagement or slip, as when the bead 2' is the part engaged by lever or cam, nor does 85 the present construction and arrangement require nicety of adjustment of the parts in order to obviate failure of engagement, as when, for instance, the edge of the cover flange or rim is the part to be engaged. 90

Having thus described my invention, I claim as new and desire to secure by Letters Patent.

1. The combination with a blacking box and the cover therefor having a flange engaging the periphery of said box, of a lever interposed between said flange and periphery, said lever having a load-end extending above the upper edge of said box and a power-end extending below the said flange, 95 bearing-lugs which are integral struck out portions of said flange, a pocket in said flange to receive said load-end, and stops on said lever limiting the upward movement of its power-end to substantially a horizontal position. 100

2. The combination with a box of the class described and a flanged cover therefor, said flange engaging a vertical side of said box and provided with a cut out portion, 110 lugs at the ends of said cut portion, said lugs being integral portions struck out of

said flange, an integral lever having ears thereon, a pivot pin mounted on said lugs and engaging said ears, and a depression to receive the load-end of said lever, said depression formed in the inner side of said flange and arranged above the upper edge of said box when said cover is fitted onto said box.

In testimony whereof I have hereunto set my hand in the presence of two subscribing 10 witnesses.

FRANS O. LIDHOLM.
